A. P. STARK

FIREARM HOLDING AND TRIGGER ACTUATING DEVICE

Filed Dec. 27, 1926

UNITED STATES PATENT OFFICE.

ALPHA PRENTIST STARK, OF PAMPA, TEXAS.

FIREARM-HOLDING AND TRIGGER-ACTUATING DEVICE.

Application filed December 27, 1926. Serial No. 157,190.

This invention relates to a device primarily adapted for use in the holding of a pistol or revolver together with means for actuating the trigger thereof, the invention being especially useful in banks, jewelry stores, and other public places ever in danger of robbers.

The invention further aims to provide a device of this character that may be conveniently arranged beneath the counter of a bank or store so that in the event a robber attempts to hold up a bank cashier, or salesman, it will only be necessary that the trigger of the pistol or revolver be actuated with the result that the hold up party is either killed or seriously wounded.

A further and important object resides in the provision of a device of this character that is extremely simple of construction, inexpensive of manufacture, and one that may be employed in conjunction with conventional types of pistols and revolvers.

With the foregoing and other objects in view as the nature of the invention will be better understood, the same comprises the novel form, combination and arrangement of parts hereinafter more fully described, shown in the accompanying drawing and claimed.

In the drawing wherein like reference characters indicate corresponding parts:

The figure is a perspective of a fire arm holding and trigger actuating device constructed in accordance with the present invention.

Now, having particular reference to the drawing, my novel device consists of a skeleton frame 5 preferably of angle bar formation of any suitable height and preferably of square or rectangular shape in cross section.

Rigidly secured to the inner side of the rearmost vertical bars of the frame 5 is an inwardly extending slightly inclined U-shaped hanger bracket 6 the main bar of which is curved rearwardly intermediate its ends as to provide one member 7 of a two piece clamp within which the handle of a pistol or revolver A is to be disposed. For association with this member 7 of the clamp is a similarly shaped movable section 8 detachably associated with bracket 6 by reason of bolt and nut connections 9-9. When the handle of the pistol or revolver is disposed between the clamp sections as indicated in the drawing, the barrel thereof will extend

upwardly at an incline so that the same may be secured to the upper end of the frame 5 by reason of a clamp 10 or other suitable means.

Suitably connected to the trigger of the pistol or revolver is a cross pin 11 to the ends of which are connected the ends of an elongated bail member 12 that extends rearwardly beneath the bracket 6 and to the rear end of which is adjustably connected one end of a bar 13. Disposed upon the floor or bank or store within which the device is installed is a foot actuating device consisting of a base plate 14 to the forward end of which is pivotally connected a foot lever 15, the rear end of which is maintained in elevated position by reason of an expansible coil spring 16 disposed between the lever and said base plate. The upper edge of this lever 15 is formed with a vertical extension 17 to which the rear end of the bar 13 is loosely connected as indicated in the drawing. Obviously, when the foot lever 15 is depressed, a pull will be occasioned upon the bail 12 for so actuating the trigger as to cause the discharge of the pistol or revolver.

It will thus be seen that I have provided a highly novel, simple, and efficient fire arm holding and trigger actuated device that is well adapted for all the purposes heretofore designated, even though I have herein shown and described the invention as consisting of certain detail structural elements, it is nevertheless to be understood that minor changes may be made therein without effecting the spirit and scope of the appended claims.

Having thus described the invention, what I claim as new is:—

1. In a device of the class described, a frame, a substantially U-shaped bracket secured on the frame, the crown portion of the bracket being shaped to receive the butt of a revolver, a complementary clamp for rigidly securing the butt on said bracket, an additional clamp for securing the barrel on the front of the frame, and remotely operable means for actuating the trigger of the revolver.

2. In a device of the class described, a frame, a U-shaped bracket secured on the frame, the crown portion of the bracket being shaped to receive the butt of the revolver, a complementary clamp for rigidly securing the butt on the bracket, a clamp

- for securing the barrel on the front of the frame, slideable bails, a pin extending transversely between the free end of the bail and through the trigger guard of a revolver, 5 said pin adapted for cooperation with the trigger, a rod secured at one end to the rear end of the bail, and a foot lever operatively connected with the other end of the rod to actuate the bail and the trigger.
- 10 3. In a device of the class described, a frame, a substantially U-shaped bracket, the free end of the arms thereof being secured to the rear side of the frame at the intermediate portion thereof, the crown portion 15 of the U-shaped bracket being shaped to receive the butt of a revolver, a comple-

mentary clamp for securing the butt on the bracket, the end of the barrel of the revolver adapted to rest on the top of the front of the frame, a clamp for securing the barrel 20 on the frame, a bail disposed below the bracket, a pin extending transversely through the free end of the bail and through the trigger guard for cooperation with the trigger, a rod secured at one end to the rear 25 end of the bail, and a foot lever operatively connected with the other end of the rod for actuating the bail whereby to pull the trigger.

In testimony whereof I affix my signature.

ALPHA PRENTIST STARK.
